LEVEL-CONTROLLING DEVICE FOR
CONTAINERS OF LIQUID

Otto Eckerle, Am Bergwald 3, Malsch, Germany, and
Helmut Weinzierl, Rastatt, Germany; said Weinzierl as-
signor to said Eckerle

Filed Feb. 11, 1965, Ser. No. 431,900
2 Claims. (Cl. 200—84)

The present invention deals with a level-controlling device for reservoirs or tanks designed to turn a feed pump on and off by means of an electric spring contact switch, mechanically actuated by means of a float.

In the conventional devices of the prior art, disturbances and variations in setting the switches are caused to a large extent as a result of jolts or in the process of assembly, repairs and inspection thereof to a degree often so considerable that the operation of the switch is interrupted.

It is the primary object of the present invention to provide a device in which the accuracy of the settings is unaffected by temperature variations, vibrations, by the assembly of the device and inspections thereof.

Another object of the invention is to eliminate these inaccuracies by providing a holder or support member made of one piece and mounting the float bearing and the switch with the switch tongue thereon. Because of this provision, normally detrimental influences of the type described above cannot change the setting of the device because the two essential elements, i.e. the float bearing and the switch tongue bearing, are disposed on the same body so that a mutual displacement thereof becomes impossible.

Still another object of the invention is to provide the holder or support member with a fastening plate tightly screwed onto the opening of a terminal or connection box, preferably made of plastic which accommodates the elements most susceptible to disturbances. Since these elements are usually the switch contacts as well as the electric connection, the fastening plate is suitably disposed between the float bearing and the switch. In such an instance, the plate is provided with openings through which extend tongue-actuating members controlled by the float arm.

Other objects and advantages of the invention are taught by the following description which describes a preferred embodiment thereof in detail in connection with the accompanying drawings, wherein

FIGURE 1 shows a top plan view of a level-controlling device according to the present invention;

FIGURE 2 is a vertical cross-sectional view taken along line II—II of FIGURE 1;

FIGURE 3 is a vertical cross-sectional view taken along line III—III of FIGURE 1, and

FIGURE 4 illustrates schematically the actuation of the switch tongue in different positions of the float.

In the drawings wherein like reference numerals describe the same or equivalent structures it will become apparent to those skilled in the art, particularly from FIGURES 2 and 3, that the bearing 10 of the float arm 11 as well as the switch lever 12 and the switch 13 operated by it are carried by a common holder or support member 14. The latter has between the switch lever 12 and the float bearing 10 a fastening plate 15 which is screwed in a sealing manner onto the opening 17 of a terminal or connection box 18 by means of screws 16. This box is preferably made of plastic. The switch lever 12 which is protectively received by or accommodated in the connection box is pivotally held at the holder or support member about an axis 20 parallel to the axis of rotation of the float. The switch lever acts upon the switch 13 by means of an adjusting screw 21. The actuation or

2

operation of the switch lever itself is effected by the float arm 11 by means of two control rods 22 and 23 which extend upwardly through apertures in the fastening plate 15 which represents a bearing. The control rods 22 and 23 are secured to the float arm 11 with the ends thereof facing away from the switch lever at opposite sides of the float bearing. Rod 22 is in an operative engagement with the switch lever when the float 6 is lowered downwardly from the horizontal position 24 thereof (FIG. 4). The other control rod 23 is in engagement with the switch lever when the float is raised above the horizontal position so that the switch lever 12 will actuate the switch 13 off and on whenever the operating range is exceeded either upwardly or downwardly.

15 A third rod 30 is disposed adjacent the holder or support member 14 and extends between the control rods 22 and 23 through a bore in the fastening plate to the switch lever. The rod 30 rests with the other end thereof and with the interposition of an adjusting screw 31 on the free end of a bent bimetallic 32 which actuates the rod and is secured to the holder or support member.

20 The holder or support member 14 with a bearing surface 33 thereof also serves as an abutment for the pre-tensioned spring 9 of a trip rod 34 which raises the float into its horizontal position, acts on the end of the float arm 11 facing away from the float and is connected with a tripping pin or plunger 7 by means of a spring 8.

25 Due to the fact that all the essential control elements are disposed and guided at the same holder or support member, mutual displacements during the assembly, during an inspection or because of vibrations are avoided and the accuracy of the setting is not affected.

30 In order to achieve a simple connection between the float 6 and the float arm 11, the latter is provided with a bent hook 35 which receives the float with a snapping effect and which expediently comprises a bead or stiffening corrugation 37 enclosing the sealing reinforcement 36 of the float and preventing the axial displacement of the latter.

35 In operation, the float rests in the liquid in a reservoir or tank, and the bimetallic strip 32 is submerged in the liquid.

40 Referring to FIG. 4, four positions for the float 6 are shown. The pump is energized only when the float 6 is between an upper and lower intermediate position such as the two middle positions in FIG. 4. If the liquid level in the reservoir rises above the upper intermediate level and the float 6 rises to the uppermost position shown, the pump is turned off. As the float rises and the float arm 11 pivots about bearing 10 in a counter-clockwise direction, actuating rod 23 is pressed against the switch lever 12, opening the switch contacts and de-energizing the pump. As the float 6 falls, the actuating rod 23 is lowered, and the switch contacts close, energizing the pump.

45 If the liquid level were to fall below the lower intermediate level to the lowermost position shown in FIG. 4, actuating control rod 22 would similarly be pressed upward against the switch lever 12, opening the switch contacts, and de-energizing the pump. To start the pump again, it is necessary to lift the float 6 using button 7 and rod 34, pressing the button until the float 6 is raised to an intermediate position and the pump is energized.

50 In normal operation, oil or liquid is always intended to be present in the reservoir, and the float 6 is maintained at an intermediate position. Only when some disturbance or mechanical malfunction occurs does the liquid level in the system fall below the lower intermediate position. Thus it is solely a safety measure to prevent pump operation during the disturbance.

55 Similarly the bimetallic strip 32 is a safety device. With some liquid systems, particularly oil feeding systems, it is desirable to turn the pump off if the liquid in the sys-

tem rises above a certain temperature. The bimetallic strip 32 actuates rod 30, pressing it against the switch lever 12 and de-energizing the pump when the temperature has risen above a certain level.

While we have disclosed the form of mechanism presently preferred by us for carrying the invention into practice, numerous modifications, alterations and substitutions of equivalents will occur to those skilled in the art, after a study of the foregoing specification. Hence the disclosure should be taken in an illustrative rather than a limiting sense; and it is our desire and intention to reserve all modifications and substitutions of equivalents within the scope of the subjoined claims.

Having now fully disclosed the invention, what we claim and desire to secure by Letters Patent is:

1. A switch device for making and breaking an electric circuit as a function of properties of liquid in a container, comprising: a one-piece support; a float arm mounted on said support pivotably about a float pivot axis; a float attached to said float arm away from said float pivot axis; a switch arm mounted on said support pivotably about a switch arm pivot axis; said switch arm pivot axis being removed from said float pivot axis; said float pivot axis being substantially parallel to said switch arm pivot axis; two rods, one pivotably connected to the float arm on one side of the float pivot axis, one pivotably connected to the float arm on the other side of the float pivot axis; both rods abutting on said switch arm in a sliding pushing contact on the same side of said switch arm pivot axis when said switch arm is in its cir-

5 cuit making position, a guide means forming an integral part of said one-piece support to prevent lateral vibration and deflection of said rod means; said guide means being a plate having a guide hole for each rod; said plate located between said float arm and said switch arm; each rod passing through its respective hole; said holes providing lateral support to said rods; and a make-break switch means operated by the movement of said switch arm.

10 2. A switch device as claimed in claim 1, further comprising a third rod extending through a guide hole in said plate and abutable on said switch arm on said same side and a bimetallic strip connected at one end to said support at a submerging position, connected at its other end to said third rod and deflectable according to temperature change in the axial direction of said third rod.
